RUG CROQUET WICKET

L Julian Smith, Long Beach, Calif.

Application February 5, 1937, Serial No. 124,225

2 Claims. (Cl. 273—56)

This invention relates to a croquet wicket which is adapted to be mounted or positioned on a rug in such a manner so as not to injure the rug, either in placing the wicket, or in playing 5 the game.

An object of my invention is to provide a croquet wicket with outwardly extending spurs at the lower end thereof, which spurs project into a rug.

10 Another object is to provide a croquet wicket formed of wire, the natural spring of the wire serving to project and hold outwardly extending spurs into the nap of a rug.

Still another object is to provide a croquet 15 wicket of the character stated which is simple in construction, inexpensive to manufacture and effective in use.

Other objects and advantages and features of 20 the invention may appear from the accompanying drawing, the subjoined detailed description and the appended claims.

In the drawing:

Figure 1 is a side elevation of my wicket in position on a rug.

25 Figure 2 is a bottom plan view of the wicket.

Figure 3 is a fragmentary transverse sectional view of one of the feet and showing a modified form of spur construction.

Referring more particularly to the drawing, 30 the numeral 1 indicates a substantially U shaped wire, forming the wicket through which a croquet ball is driven. The wicket includes legs 2 and 3, on the lower end of which are fixedly attached cup-shaped feet 4 and 5. The feet 4 and 35 5, are preferably concave and they bear against the rug for the purpose of stabilizing

the wire 1, when in use. Spurs 6 and 7 are fixedly attached either to the foot 4 or 5, or to the lower end of the legs 2 and 3. The feet are soldered, welded or otherwise fixedly attached to the lower end of the legs 2 and 3, and the spurs 6 and 7, 5 are soldered, welded or otherwise fixedly attached to either the feet or to the lower end of the legs. The spurs 6 and 7, extend downwardly and outwardly from the feet 4 and 5 and said spurs are substantially in alignment in the plane 10 of the wicket. It will thus be evident that when the spurs are injected into the rug or carpet, the feet 4 and 5 will be placed tightly against the surface of the carpet and the spring of the wire 1, will hold the spur securely in the position 15 as shown in Figure 1. In Figure 3, the leg 8 is swaged above and below the cup 9, as shown at 10. The spur 11 is integrally formed with the leg 8, and the position and arrangement of this spur is substantially identical to the construction 20 previously described.

Having described my invention, I claim:

1. A rug croquet wicket comprising a wire arch, a substantially circular foot on the lower end of each leg of the arch, the lower end of each leg of the arch being formed as a spur, said spurs projecting downwardly and outwardly and being arranged in the plane of the arch. 25

2. A rug croquet wicket comprising a wire arch, a spur integrally formed on the lower end of each leg of the arch, said spurs projecting downwardly and arranged in the plane of the arch, a cup shaped foot mounted adjacent the bottom of each leg and above the spur. 30

L JULIAN SMITH. 35
